GT-R Billet Intake Manifold for 08+ 3.8L V6 GTR R35 VR38DETT VR38 3.8 Twin TURBOhttps://www.amazon.com/Billet-Intake-Manifold-VR38DETT-TURBO/dp/B082XHN4TK/ref=sr_1_1?keywords=billet+VR38+intake+manifold+for+GTR+R35&gid=1582842469&s=automotive&sr=1-1 (Year: 2019).*

Primary Examiner — T Chase Nelson*Assistant Examiner* — Ania Aman(74) *Attorney, Agent, or Firm* — Loza & Loza, LLP;
Heidi L. Eisenhut(57) **CLAIM**

The ornamental design for an intake manifold, as shown and described.

DESCRIPTION

FIG. 1 is a front, right, top perspective view of an intake manifold;

FIG. 2 is a rear, left, bottom perspective view of the intake manifold of FIG. 1;

FIG. 3 is a right side elevation view of the intake manifold of FIG. 1;

FIG. 4 is a left side elevation view of the intake manifold of FIG. 1;

FIG. 5 is a front elevation view of the intake manifold of FIG. 1;

FIG. 6 is a rear elevation view of the intake manifold of FIG. 1;

FIG. 7 is a top plan view of the intake manifold of FIG. 1; and,

FIG. 8 is a bottom plan view of the intake manifold of FIG. 1.

The broken lines show features of the intake manifold that form no part of the claimed design.
